INVENTOR

BY *Victor J. Evans* ATTORNEY

UNITED STATES PATENT OFFICE.

DAVID NELSON, OF BROOKLYN, NEW YORK.

TOBACCO PIPE.

Application filed March 1, 1921. Serial No. 448,841.

To all whom it may concern:

Be it known that I, DAVID NELSON, a citizen of Sweden, residing at Brooklyn, in the county of Kings and State of New York, have invented new and useful Improvements in Tobacco Pipes, of which the following is a specification.

This invention relates to tobacco-pipes.

Some of the objects of the present invention are: to produce a pipe of the character mentioned whose stem is constructed so that the pipe may be readily cleaned of all nicotine accumulations; to produce a pipe with a stem which is divided longitudinally to provide readily separable sections one of which sections is formed integrally with the bottom of the bowl of the pipe while the other section forms a slip joint with said bowl, to afford a more thoroughly useful and more practical pipe. With these and other objects in view the invention resides in the particular provision, construction and arrangement of parts hereinafter more fully described and illustrated in the accompanying drawing, in which:

Figure 1 is a side elevation of the tobacco-pipe of the present invention.

Figure 2 is a central longitudinal sectional view of the pipe.

Figure 3 is an enlarged transverse sectional view on the line 3—3, Figure 2.

Referring more particularly to the drawing, it will be manifest that, the pipe of the present invention as constructed includes a bowl 10 having the usual tobacco cavity 11. The bowl 10 supports a stem 12. The stem 12 is divided longitudinally to provide a section 13 and a section 14. The section 13 is formed integrally with the bowl 10, the said section 13 extending outwardly from the bottom of the bowl in continuation thereof. This latter feature of construction is desirable in a pipe having a stem of separable sections since the bowl will be a complete, undivided receptacle for the tobacco, thus eliminating draft spaces except at the top of the bowl. The section 13 is mortised as at 15, and grooved as at 16. The other section 14 of the stem 10 has a tenon 17

which extends throughout its length. A 50 groove 18 in the tenon 17 with the groove 16 forms a draft passage when the sections 13 and 14 are brought into stem forming relation, the draft passage so formed will be in communication with the interior of the 55 bowl 10 through the aperture 19. One end of the section 14 has a reduced extension 20 and shoulder 21. The extension 20 is insertable in the aperture 19, and the shoulder 21 abuts the wall of the bowl, the arrangement being in the nature of a slip joint. This latter feature and the dove-tail joint between the sections 13 and 14 afford a most effective arrangement for a free drawing pipe, the draft of which being through the 60 bowl from the open top thereof and then through the stem 10. The stem section 14 may be provided with a ring member 22 which will encircle the other section 13. The ring member 22 will serve as a grip for the 65 quick and easy separation of the sections 13 and 14.

It is to be understood that the pipe of the present invention may be made of any suitable and desirable material; that the 75 stem may be straight or curved; that the stem may be without the mouth piece 23 shown in the drawing.

What is claimed is:

A tobacco-pipe comprising a bowl having 80 an aperture which opens to the interior of the bowl, a stem of longitudinally separable interfitting sections, one of said sections being slidable on the other section and having a reduced extension and a shoulder, the extension fitting in said aperture and the shoulder abutting the wall thereof, said sections forming a draft passage which communicates directly with the interior of said bowl, and a ring member secured to the 85 slideable section and capable of encircling the other section and being in the nature of a grip for the ready separation of said sections.

In testimony whereof I hereby affix my 95 signature.

DAVID NELSON.
